UNITED STATES PATENT OFFICE

110,257

DESIGN FOR A PENNANT-LIKE DEVICE

Frank L. Ogg, Los Angeles, Calif.

Application March 9, 1938, Serial No. 75,693

Term of patent 3½ years

To all whom it may concern:

Be it known that I, Frank L. Ogg, a citizen of the United States and a resident of the city of Los Angeles, in the county of Los Angeles and State of California, have invented a new, original, and ornamental Design for a Pennant-Like Device, of which the following is a specification, reference being had to the accompanying drawing, forming part thereof.

Fig. 1 is a side elevational view of a pennant-like device showing my new design.

Fig. 2 is a plan view.

The other side of the device, to that shown in Fig. 1, is substantially the same; and the front view of the cross-like element appears the same as the side view shown in Fig. 1.

I claim:

The ornamental design for a pennant-like device substantially as shown and described.

FRANK L. OGG.

It is hereby certified that error appears in the above numbered patent requiring correction as follows: In the drawing, Figure 1 should appear as shown below instead of as shown in the patent -

and that the said Letters Patent should be read with this correction therein that the same may conform to the record of the case in the Patent Office.

Signed and sealed this 30th day of August, A. D. 1938.

Henry Van Arsdale
